UNITED STATES PATENT OFFICE.

CHAUNCEY H. BOOTON, OF GALLIPOLIS, OHIO, ASSIGNOR OF ONE-FOURTH
TO GEORGE PARENT, OF SAME PLACE.

AUTOMATIC REGISTER-GAGE FOR PRINTING-PRESSES.

SPECIFICATION forming part of Letters Patent No. 674,532, dated May 21, 1901.

Application filed August 18, 1900. Serial No. 27,315. (No model.)

To all whom it may concern:

Be it known that I, CHAUNCEY H. BOOTON, a citizen of the United States, residing at Gallipolis, in the county of Gallia and State of Ohio, have invented a new and useful Automatic Register-Gage for Printing-Presses, of which the following is a specification.

This invention relates to an automatically-operating register-gage for printing-presses, and contemplates the provision of simple and effective means of this character for causing an accurate registration of the sheet without requiring precise manual adjustment thereof and permitting a press to be run at a materially greater rate of speed than heretofore with a corresponding increase in the output of work within a specified or given time and a more satisfactory result in the quality of the work and marked economy in the use of material, the gage being applicable to any form of platen-press and used only on one side of the tympan and occupying no more space than the ordinary side pins now in use and serving to place the sheet in proper position irrespective of a regular or irregular feed of the same.

The invention consists in the construction, combination, and general organization of the several parts of the gage in general and in detail, which will be more fully hereinafter described and claimed, and subject to a wide range of modification, which will be indicated hereinafter by reference to the several variations, and also indicating that other changes in the form, size, proportions, and minor details may be resorted to without departing from the principle of the invention.

In the drawings, Figure 1 is a perspective view of a portion of a press, showing the gage forming the subject-matter of this invention applied thereto in operative position. Fig. 2 is a detail perspective view of the gage. Fig. 3 is a top plan view of the same. Fig. 4 is a section on the line 4-4, Fig. 3. Fig. 5 is a section on the line 5-5, Fig. 3. Fig. 6 is a section on the line 6-6, Fig. 3. Fig. 7 is a detail perspective view of parts of the device, showing a modification in the construction. Fig. 8 is a detail perspective view of a portion of the operating-arm, showing a further modification. Fig. 9 is a plan view of a por-

tion of the improved device, showing a slight modification.

Similar numerals of reference are employed to indicate corresponding parts in the several views.

The numeral 1 designates a supporting-plate, preferably constructed of thin metal of a non-corrosive nature and having adjacent one end, near the outer edge, a pair of fulcrum ears or lugs 2, having a longitudinal direction relatively to the plate and spaced apart from each other a suitable distance for the pivotal reception of the rear bifurcated terminal 3 of an operating-arm 4 and normally held outward or away from the plane of the plate 1 by a spring 5, engaging the pivot thereof and of such strength to always cause the said arm to return to its outward normal position when free to do so. This operating-arm can be constructed in many different designs and be supplied with various attachments to render it more convenient in application to different styles of printing-presses and more efficient in its operation. One of the most important of these attachments or convenient provisions consists in a sliding extension 6, having a rear terminal guide 7, movable on the said arm and both engaged by a locking or clamping slide 8 for holding the parts against accidental movement after a desired adjustment has been obtained. It will be observed that by the use of this attachment the arm may be operatively lengthened or shortened to compensate for the proportions of various kinds of presses, and at its inner end the said extension has an outward projection 9 at an angle thereto for contact with a gripper or other part of a press, which will cause the arm as an entirety to be pressed close to the plate 1, and thus actuate the remaining essential parts of the gage that will be hereinafter set forth. The projection 9 is preferably formed of harder material than the extension or the arm to make it more durable, and it will be obvious that in some instances the said projection could be used on the arm-terminal direct and dispense with the extension. Another obvious change is indicated by Fig. 8 and consists in mounting an antifrictional bearing-roller 10 in the inner or contacting terminal of the arm

for use in connection with that class of presses that do not employ grippers and to bear against the press-body or furniture adjacent the tympan, and in this instance the 5 said arm will be used without the extension, though there may be instances where this feature of the roller could be effectively employed in connection with the said extension, and such use of the roller is contemplated.

10 At the inner end of the plate 1 transverse guides 11 are secured and have their opposing edges inclined to form a dovetail seat for the freely-movable reception of a slide 12, having opposite beveled side edges and an 15 inner angular head 13 at a right angle thereto and providing what may be concretely termed a "pusher" or "slidable sheet-placer." The slide 12 has an outwardly-projecting stud 14 to receive the inner end of a retractile 20 spring 15, attached at its opposite end to a suitable projection 16 on the plate 1. This spring may at times be dispensed with, as will be hereinafter set forth; but when used it operates to return the pusher or placer to 25 normal position, and the automatic operation of the latter device to perform the function for which it is devised is caused by the operating-arm and intermediate connections between the latter and said pusher or placer.

30 The head of the pusher or placer is engaged by the outwardly-deflected inner terminal of a controlling-lever 17, which is loosely disposed on and unattached to any part of the slide or head, the rear or opposite terminal 35 of the said lever being pivoted to or fulcrumed on the plate 1. The outer edge portion of the lever, adjacent the pivot or fulcrum thereof, is provided with an open socket 18, as clearly shown by Figs. 2 and 3, and 40 loosely engaging therewith is a ball 19 on the inner end of a connecting screw-shank 20, having a polygonal fixed collar 21 for adjusting the same relatively to a socket 22, carried by a ball 23 and maintained in adjusted position by a jam-nut 24. The ball 23 loosely engages an open socket 25 on the inner edge of the arm 4, and thus a double ball-and-socket connection is formed between the lever and arm, which has a normal upward in- 45 elination from the lever toward the arm and the alternate depression of the arm, and the return of the same to its normal position in an automatic manner by the action of the spring 5 will cause a differentiation in the 50 distance between the contiguous edges of the lever and arm and alternately force the lever inward and draw the said lever outward and correspondingly move the pusher or placer inward and free the latter for outward normal position. When no spring is used for 55 retracting the pusher or placer, the slide thereof will be provided with a pin 26, as shown by Fig. 9, for engagement with the free end of the lever to return the said pusher or placer to normal position, and the sockets for the balls at the opposite ends of the connection in this instance will be closed, as

shown. It will also be understood that the forms of connections set forth will prevent jarring or abrupt vibration of the lever, and 70 the pusher or placer will consequently always have a regular stroke, and this latter desirable movement of the lever will also be due largely to the elongated construction of the arm, and therefore no matter how rapidly the 75 press may be running the pusher or placer will be easily moving and engaging the fed sheet with regularity of stroke and accurately place the same without hand manipulation or liability of knocking it too far over and 80 out of proper registering alignment.

In Fig. 7 the arm is shown provided with a closed socket 27, and the lever will also have a similar socket in this particular arrangement, and between these two sockets a stiff 85 link 28 is interposed and formed with terminal balls 29, located in said sockets. From this showing it is to be understood that the adjustable feature of the ball-and-socket connection is not essential to the practical operation 90 of the gage, and when the last-described ball-and-socket connection is used the retractile spring for the pusher or placer can be dispensed with and the pin 26 (shown by Fig. 3) substituted in lieu thereof and which 95 is an obvious substitution.

In applying the improved device to the tympan, as shown, it is preferred that the tympan-sheet be of a strong and durable nature to support the gage attachment without 100 tearing. The under side of the plate 1 is supplied with a layer of glue or other adhesive material and placed on the said tympan-sheet, and in the event that the device is not evenly or regularly positioned the irregularity can be rectified by adjusting the screw-shank 20 relatively to the socket 22 to cause the pusher or placer to have a regular stroke. The operating-arm is regularly positioned relatively to the gripper at one side or other 110 part, and the sheet to be printed is fed to the machine and rests against the usual pins or stops extending outwardly beyond the tympan-sheet, and as the parts of the press are moving the operating-arm is pressed toward 115 the plate 1, and thereby actuates the pusher or placer to dispose the fed sheet in proper registering position in an easy yet quick manner without jar or jolt. The portion of the head of the placer or pusher that normally 120 rests close to or against the inner edge of the plate 1 projects slightly beyond the inner plane of said plate to compensate for the layer of glue or other adhesive material and cause the innermost edge of said head to bear closely 125 against the tympan-sheet, and thereby always insure engagement of the head with the sheet edge and prevent the latter from working under the plate. The pressure on the operating-arm will be exerted against the inner free end 130 of the same in the direction of the outer side of the same and not against the end in a longitudinal direction, and consequently the inner end of the plate will be forced firmly

against the tympan-sheet, and thereby also tend to hold the head of the pusher or placer in close operating relation to the tympan-sheet.

5 It will be observed that the gage has been devised and is equipped with means for overcoming the complex structure and unsatisfactory operation of previous devices of a similar character, and it will be particularly noted 10 that the organization of coacting members are compact and close in without material projection to avoid interference with the working parts of a press and that it occupies very little room. The use of only one of the 15 devices is necessary, and the cost of manufacture and application is reduced to a minimum from a comparative standpoint. In fact, the presses are permitted to run at such a greater degree of speed with positive results and accurate work by the application of the gage embodying the features of the invention that the operation of the press of whatever kind is materially reduced in cost, as the capacity of the same is increased by the rapid feed 20 permitted by the gage with accurate results and a better quality of work than has heretofore been attainable with a slower movement.

Many other advantages will appear to those using the improved device, and it will be appreciated that the gage is not confined in its 25 application to any particular style or kind of press.

Having thus described the invention, what is claimed as new is—

35 1. An automatic register-gage for printing-presses, comprising a pusher or placer having a sliding movement in a straight plane, an automatically outwardly impelled operating-arm actuated by a portion of the press to have 40 a reverse movement, and means movably connected and at an angle to both the pusher or placer and arm for transmitting motion from the latter to the former.

2. An automatic register-gage for printing-45 presses, comprising a pusher or placer, an operating-arm arranged at an angle to the latter and actuated by a portion of the press, and loose movable connecting devices between the pusher or placer and the arm at an angle 50 to both devices to translate and convert the compressing movement of the latter into a transversely-sliding movement of the pusher or placer.

3. An automatic register-gage for printing-55 presses, comprising a pusher or placer movable transversely of a tympan, an operating-arm for said placer or pusher having a compressing movement toward the latter and having a free end to contact with a portion 60 of the press, and an angularly-disposed connecting device having its terminals in movable relation to the pusher or placer and arm.

4. An automatic register-gage for printing-65 presses, comprising a pusher or placer, and an actuating-arm in operative relation thereto and having a normal outward oblique angle to the portion of the press supporting the

same, the arm being moved by a portion of the press and disposed at an angle to the pusher or placer.

5. The combination with a tympan, of an automatically-operating register-gage therefor arranged at one side only thereof and having a horizontally-disposed transversely-slid- 75 able pusher or placer, and an arm operatively controlling said pusher or placer and having a free end in position for contact with a portion of the press, said pusher or placer being entirely separate from the arm and operated in a plane at an angle to the latter. 80

6. An automatic registering-gage for a printing-press, comprising a sheet placer or pusher, a sheet-rest on which said placer or pusher is mounted, and an operating-arm for said pusher or placer entirely separate from 85 the latter and acting by its movement to bring the sheet-contacting end of the latter closer to said sheet-support.

7. An automatic registering-gage for a printing-press, comprising a sheet placer or 90 pusher, a support therefor, a sheet-receiving device on which said support and pusher or placer are mounted, and an operating-arm movably attached to the extremity of the support opposite that having the pusher or 95 placer thereon and structurally and supportedly independent of the latter, whereby the movement of the arm will bring the sheet-contact extremity of the pusher or placer in closer operative relation to the said sheet-receiving device. 100

8. An automatic registering-gage for a printing-press comprising a sheet-receiving device, a support adhesively applied thereto, a sheet pusher or placer horizontally disposed 105 slidably mounted on the support and having a sheet-contacting extremity with an upper angular portion normally projecting inwardly beyond the plane of the attached side of said support, and an operating-arm for said pusher 110 or placer actuated by a portion of the press, whereby a close and accurate operative relation between the pusher or placer and the sheet-receiving device is established.

9. An automatic registering-gage for a 115 printing-press, comprising a sheet pusher or placer having a sliding movement, an operating-arm for said pusher or placer actuated by a portion of the press, and loose terminally-attached connecting and motion-trans- 120 mitting devices between the said arm and pusher or placer and at angle to both of the latter devices.

10. In a device of the character set forth, the combination of a sheet pusher or placer 125 having a sliding movement, a reciprocable member loosely engaging the pusher or placer, an operating-arm regularly moved by a portion of the press, and a loose connection between the said arm and the reciprocable 130 member.

11. In a device of the character set forth, the combination of a sheet pusher or placer, a reciprocable member loosely engaging the

pusher or placer, an operating-arm regularly moved by a portion of the press, and a double ball-and-socket connection between the said arm and member.

5 12. In a device of the character set forth, the combination of a sheet pusher or placer, a reciprocable member loosely engaging the pusher or placer, an operating-arm regularly moved by a portion of the press, and an adjustable ball-and-socket connection between said arm and member.

13. In a device of the character set forth, the combination of a sheet pusher or placer, and operating-arm regularly moved by a portion of the press, and adjustable motion-transmitting devices between and at an angle to both the arm and pusher or placer and having one terminal normally at a lower horizontal plane than the other.

2c 14. In a device of the character set forth, the combination of a sheet pusher or placer having a sliding movement, an operating-arm normally standing outwardly at an oblique angle to the plane of the pusher or placer and regularly moved by a portion of the press inwardly toward the latter, a controlling-lever engaging the pusher or placer, and motion-transmitting devices between the arm and the said controlling-lever.

25 15. In a device of the character set forth,

the combination of a sheet pusher or placer, an operating-arm therefor having an adjustable extension, and motion-transmitting devices between the pusher or placer and the arm.

35 16. In a device of the character set forth, the combination of a sheet pusher or placer, a controlling device loosely and operatively engaging said pusher or placer, a spring-actuated operating-arm normally standing outwardly from the plane of the pusher or placer and regularly moved by a portion of the press inwardly toward the latter, and a motion-transmitting device between the arm and the said controlling device.

40 17. In a device of the character set forth, the combination of a sheet pusher or placer, a controlling device loosely and operatively engaging said pusher or placer, and an arm in operative relation to said controlling device movable toward and outwardly from the same to alternately project and retract the said pusher or placer.

45 In testimony that I claim the foregoing as my own I have hereto affixed my signature in the presence of two witnesses.
